UNITED STATES PATENT OFFICE.

WILLIAM DALTON, OF SCHENECTADY, NEW YORK, ASSIGNOR TO AMERICAN LOCOMOTIVE COMPANY, OF NEW YORK, N. Y., A CORPORATION OF NEW YORK.

CUSHIONING APPLIANCE FOR LOCOMOTIVES.

No. 868,913.

Specification of Letters Patent.

Patented Oct. 22, 1907.

Application filed July 22, 1907. Serial No. 386,019.

To all whom it may concern:

Be it known that I, WILLIAM DALTON, of Schenectady, in the county of Schenectady and State of New York, have invented a certain new and useful Improvement 5 in Cushioning Appliances for Locomotives, of which improvement the following is a specification.

My invention relates to appliances designed to cushion the side blows of locomotives upon the rails when running at high speeds, so as to minimize the jars and 10 shocks resultant therefrom, an instance of such appliances being exemplified in Letters Patent of the United States No. 841,379, granted and issued to American Locomotive Company, as my assignee, under date of January 15, 1907.

15 The object of my present invention is to simplify and economize the appliance of said Letters Patent, while attaining the same usefully operative results.

The improvement claimed is hereinafter fully set forth.

20 In the accompanying drawings: Figure 1 is a horizontal section through a portion of a locomotive frame, illustrating an application of my invention; Fig. 2, a side view, in elevation, of the same; Figs. 3 and 5, horizontal sections through portions of locomotive frames, 25 illustrating structural modifications; and, Figs. 4 and 6, side views, in elevation, of the constructions shown in Figs. 3 and 5, respectively.

My invention is herein, as in Letters Patent No. 841,379 aforesaid, exemplified as applied in connection 30 with axles, 2, of an electric locomotive, upon which wheels, 4, are secured, and which are journaled in axle boxes, 3, in the ordinary manner. Pairs of vertical lateral flanges, 3^b and 3^c, are formed on the axle boxes, and pedestal shoes, 5^e, are fitted in the spaces or 35 recesses between said flanges. Each of the shoes, 5^e, is provided with vertical lateral flanges extending on opposite sides of one of a pair of vertical pedestal jaws, 5^b, fixed on, and constituting part of, one of the side frame members, 5, of the locomotive, the construction 40 providing for vertical movement of the pedestal jaws and shoes, relatively to the axle boxes, and being, as thus far described, one which is well known in ordinary practice.

In the construction set forth in Patent No. 841,379 45 aforesaid, the inner side flanges of the pedestal shoes are vertically recessed, and springs, interposed between and bearing on said flanges and the pedestal jaws, are fitted in the recesses of the pedestal shoes. This specific construction of parts, while satisfactorily attaining the result for which it is designed, is subject to 50 the objections that it involves an increase in the transverse length of the pedestal shoes and prevents ready access to the springs when required. These objections are effectually overcome under my present invention,

in the practice of which the pedestal shoes are not vertically recessed, and may therefore be of ordinary length transversely to the longitudinal plane of the locomotive. 55

The distance between the members of each pair of vertical lateral flanges of the pedestal shoes, 5^e, is 60 greater than the width of the pedestal jaws, so as to leave sufficient space or clearance to admit of the lateral movement of the axle boxes and shoes and the compression of the springs which are provided for resisting such lateral movement. The springs, 10^a, by which 65 resistance to side blows upon the rails is exerted, and by which the shocks and jars due thereto are cushioned, are located entirely exterior to the pedestal shoes, and are so disposed, relatively thereto and to the pedestal jaws, as to be subjected to compression by longitudinal 70 movements, that is, lateral movements relatively to the locomotive, of the axles and axle boxes in either direction.

Variations in the form and location of the cushioning springs, 10^a, may be made, in the discretion of those 75 familiar with locomotive construction, without departure from the spirit and essential feature of my invention. As shown in Figs. 1 and 2, said springs are of helical form, and abut against the outer sides of the outer flanges of the pedestal shoes and against followers, 80 10^b, which are adjustable by nuts, 10^c, on stems, 10^d, fixed in the pedestal shoes. It will be seen that the springs on the side of the locomotive shown in Figs. 1 and 2 will be compressed by movements of the axles and axle boxes in the direction of the arrows, and will 85 be understood that those on the opposite side of the locomotive will be compressed by movements of the axles and axle boxes in the opposite direction.

Figs. 3 to 6 inclusive illustrate the application of similarly operating cushioning springs, 10^a, of plate 90 form, extending longitudinally on the side frame member, and abutting, at their middle portions, on bearings, 10^b, fixed to the frame members, and, at their ends, on the adjacent pedestal shoes of two adjacent axles, when located between the axles, or on a pedestal 95 shoe at one end and a frame bearing, 10^c, at the other, when located longitudinally beyond the axles. The springs of Figs. 3 and 4 bear on the pedestal shoes on the inner sides of the pedestal jaws, 5^b, and those of Figs. 5 and 6 on the outer sides of said jaws. The 100 springs are compressed, and their resistance to side blows exerted, by the lateral movements of the axles and axle boxes, in the same manner, and with the same effect, as in the instance first described.

My present invention provides means for attaining 105 the same beneficial result of cushioning and minimizing the injurious effect of side lurching or abrupt lateral movement of locomotives when running at high speeds

as that of Patent No. 841,379, and has the further structural advantages of reducing the transverse length of the pedestal shoes and enabling the insertion, removal, and adjustment of the cushioning springs to be more readily and conveniently effected.

I claim as my invention and desire to secure by Letters Patent:

1. The combination of a locomotive axle, axle boxes in which said axle is journaled, side frame members in which the axle boxes are fitted and which, with the axle, are capable of lateral movement relatively to the side frame members, pedestal shoes engaging and movable laterally with the axle boxes, and cushioning springs disposed exteriorly to the pedestal shoes and bearing thereon and on the side frame members.
2. The combination of a locomotive axle, axle boxes in which said axle is journaled, side frame member pedestal jaws located on opposite sides of the axle boxes, shoes fitting in lateral recesses on the axle boxes and having lateral flanges extending on opposite sides of the pedestal jaws and providing space or clearance for lateral movement, and cushioning springs disposed exteriorly to the

shoes and compressible between said shoes and the side frame members, in and by lateral traverse of the axle boxes.

25

3. The combination of a locomotive axle, axle boxes in which said axle is journaled, side frame members in which the axle boxes are fitted, and which, with the axle, are capable of lateral movement relatively to the side frame members, pedestal shoes engaging and movable laterally with the axle boxes, and cushioning springs disposed exteriorly to the pedestal shoes and bearing thereon and on the side frame members.

30

4. The combination of a locomotive axle, axle boxes in which said axle is journaled, side frame member pedestal jaws located on opposite sides of the axle boxes, shoes fitting in lateral recesses in the axle boxes and having lateral flanges extending on opposite sides of the pedestal jaws and providing space or clearance for lateral movement of the axle, and plate springs extending longitudinally between bearings on the side frame members and on the shoes.

35

WILLIAM DALTON.
